ATTORNEY

UNITED STATES PATENT OFFICE.

JOSEPH HARRIS, OF CHICAGO, ILLINOIS, ASSIGNOR TO WILLIAM H. MINER, OF CHAZY, NEW YORK.

DRAFT-RIGGING YOKE.

1,249,388.

Specification of Letters Patent. Patented Dec. 11, 1917.

Application filed September 2, 1915. Serial No. 48,597.

To all whom it may concern:

Be it known that I, JOSEPH HARRIS, a citizen of the United States, residing at Chicago, in the county of Cook and State 5 of Illinois, have invented a certain new and useful Improvement in Draft-Rigging Yokes, of which the following is a full, clear, concise, and exact description, reference being had to the accompanying drawings, 10 forming a part of this specification.

This invention relates to improvements in draft rigging yokes.

An object of the invention is to provide a yoke having a hooded forward end with 15 which are associated removable keys for engaging both the upper and lower shoulders of a draw-bar.

Another object of the invention is to provide a yoke having means for attaching it 20 to any M. C. B. draw-bar whether the latter has a coupler key slot or not.

In the drawing forming a part of this specification, Figure 1 is a longitudinal sectional view of a yoke and draw-bar showing 25 my improvement in connection therewith. Fig. 2 is a top plan view of the structure shown in Fig. 1. Fig. 3 is a vertical sectional view taken on the line 3—3 of Fig. 1 and Fig. 4 is a detail perspective view of 30 one of the keys employed.

In said drawing, A denotes a cast yoke having upper and lower arms 10—11 and a hooded forward end consisting of top and bottom walls 12 and 13, and side walls 35 14—14. The draw bar 15 is shown as provided with the usual top and bottom shoulders 16 and 17, the draw-bar butt being inserted in the hood of the yoke, as will be understood. From the drawing, it will be 40 noted that the vertical distance between the top and bottom walls 12 and 13 of the hood corresponds substantially to the vertical dimension of the draw bar butt so that there is thus provided a sliding fit between the draw 45 bar butt and hood.

To connect the draw-bar and yoke under draft, I provide upper and lower, removable, keys 18—18, the same being substantially Z shape in cross-section as indicated in Fig. 50 1 and extending through correspondingly shaped slots in the side-walls 14 of the hood and cross slots 19—19 in the top and bottom walls 12 and 13 of the hood. In order to

provide sufficient strength, the side-walls 14—14 are extended at the top and bottom to 55 form shoulders 20—20 and within which portions of the Z shaped slots are formed. To retain the keys 18 in proper position any suitable means may be employed such as the heavy cotters 21—21. 60

From the preceding description, it will be seen that the yoke may be connected to any standard draw-bar having upper and lower shoulders, and avoids the necessity for the use of a coupler key. Furthermore, the section of the keys 18 is such as to afford great strength inasmuch as pull on the draw-bar against the inner horizontal portions 22 of the keys will cause only a tendency to shear the metal and not bend the same. It will 70 also be apparent that upon removal of the keys 18, the draw bar can be withdrawn without the necessity of lowering the butt and similarly the draw bar can be inserted without having to raise the butt in order to 75 effect the engagement between the yoke and draw-bar.

Under buff, the draw-bar may move inwardly independently of the yoke in a well known manner. 80

Although I have herein shown and described what I now consider the preferred embodiment of my invention, I am aware that changes and modifications may be made without departing from the spirit of the invention, and all such changes and modifications are contemplated as come within the scope of the claim appended hereto. 85

I claim:

In a device of the character described, 90 a yoke having a hooded forward end within which is adapted to be received a shoulered draw bar butt, said hooded end having side walls and top and bottom walls, the side walls being provided with slots, and a transversely extending key mounted in said slots, said key having a vertical portion and a horizontal flange, the latter resting upon a wall of the hood, the vertical portion being in alinement with a shoulder of the draw 95 bar. 100

In witness that I claim the foregoing I have hereunto subscribed my name this 14th day of August, 1915.

JOSEPH HARRIS.
